UNITED STATES PATENT OFFICE.

CHARLES E. LUCKE, OF NEW YORK, N. Y., ASSIGNOR TO WORTHINGTON PUMP AND MACHINERY CORPORATION, OF NEW YORK, N. Y., A CORPORATION OF VIRGINIA.

CONDENSING APPARATUS.

Application filed August 5, 1925. Serial No. 48,239.

This invention relates to steam condensers of the surface type, the especial object of the invention being to provide a construction of high vacuum surface condenser adapted especially for large sizes, in which each of the condenser tubes shall contribute the maximum area possible to active condensation of steam and thus reduce to a minimum the total tube surface required for a given rate of steam per hour.

In carrying out the invention, I aim especially to minimize the pressure drop between the tubes in the steam and air zones by a short path and by causing the steam to sweep all the tube surfaces substantially equally, so as to prevent any sluggish flow in any region, and to equalize the pressure drop across the steam flow paths between the tubes throughout the condenser by making these steam paths substantially equal in flow resistance. I aim, also, to present to the incoming steam a large percentage of the total condenser tubes so as to secure the maximum of condensing activity and to make this percentage of tubes presented to the incoming steam substantially constant and independent of the size of the condenser.

In attaining these specific objects, the condenser tubes are disposed in the form of a belt through which the steam passes from one side to the other, the flow resistance through this belt being uniform so that the steam will not pass through portions of the belt more freely than through other portions. The tubes in the belt may be uniform in number and spacing of tubes from the entrance side to the exit side, or the tubes may be spaced more closely on the exit side, it being necessary only that the flow resistance from the inlet to the outlet side should be the same throughout the length of the belt. Other means, however, may be employed for securing the uniform resistance to flow across the belt that is important for securing the result of uniform flow and maximum condensation from each of the tubes. This desired result of uniform flow and maximum condensation from each of the tubes may be secured by a thinner belt of tubes closely spaced or a thicker belt of tubes more widely spaced and the belt need not be continuous throughout the condenser, but may be interrupted by a plate or plates and the uniform flow resistance through the active portion

of the tube belt still be maintained. The belt will preferably be formed in folds or convolutions to provide large tube area within a certain condenser dimension with free admission of steam to a large percentage of the tube surface, and these folds or convolutions may be of any suitable shape and adapted to a shell of any desired form. The folds or convolutions will be so arranged as to provide equal access of steam to all the tubes of the outer row on the steam side of the belt and so as to provide equal freedom of escape of air from all the tubes on the outlet or air side of the belt. It is preferable that all steam flow areas should be proportioned to the number of tubes supplied by steam from any particular section of the steam flow passage, so that the steam velocity will be the same in entering the tube belt and likewise the air spaces between the tube folds will preferably be widest at the exit end of the air passage, which aids in securing a compact construction and reducing the total size of the condenser.

In accordance with the present invention, the general features described above are arranged in such a manner as to provide for free access of steam to the condensate water falling from the tube bank to the hot-well, and means are provided below the tube bank for dividing up the falling condensate so as to secure the thorough heating of the condensate on its way to the hot-well by the admixture of steam with the divided or sprayed falling condensate. The air also is taken off from the tube bank so that the condensate is delivered as near the temperature of the exhaust steam as possible. The arrangement of the tube bank and air off-take, also, is such that air separated by condensation of the steam is taken off above the condensate spray plate with the free passage of air to the air off-take from the entire bank of tubes, so as to avoid the increase of the air partial pressure in the hot-well and the lowering of the temperature of the condensate by contact with such air. The division of the condensate by this spray or rain plate also aids in extraction of the air from the condensate and reduces the amount of air that may be carried into the hot-well with the condensate. I preferably provide also for efficient cooling of the air and further condensation of vapors passing from the

tube bank with the air, by combining with the tube bank an air cooler within the condenser.

For a full understanding of the invention, 5 there are shown in the accompanying drawings forming a part of this specification forms of condensers embodying my invention in preferred forms, and these constructions will now be described in detail and the 10 features forming the invention then be specifically pointed out in the claims.

In the drawings—

Figure 1 is a diagrammatic cross-sectional view showing a simple form of condenser 15 embodying the broader features of the invention;

Figures 2, 3 and 4 are views similar to Fig. 1, showing modified forms of the same 20 general character as the condenser of Fig. 1, but with provision for admission of steam to the hot-well on both sides of the tube bank.

Figures 5, 6 and 7 are similar views, showing modified forms with an air cooler 25 combined with the tube bank and spray plate.

Figures 8 and 8^a are details of the plate 30 perforations.

Referring now to the drawings, A is the 35 condenser shell, B the steam inlet, C the hot-well, and *a* the air offtake, preferably consisting of a slotted or perforated pipe connected outside the casing to the usual air 40 ejector or vacuum pump of any form. Tube belt D, as shown in Fig. 1, is a shallow continuous bank of tubes, shown as of uniform 45 depth, in which case the spacing of the tubes preferably will be uniform throughout the length of the belt so as to secure uniform flow resistance throughout the belt. The 50 tube belt is formed in several folds or convolutions, the steam inlet spaces 10 preferably being of decreasing width between the folds according to the extent of the tube belt to be supplied with steam from the different sections of the inlet passage, thus 55 securing a more compact construction and aiding in securing a uniform flow through the belt, and the air passages 11 on the opposite side of the belt from the steam spaces will preferably expand, increasing in size 60 toward the outlet, for free flow of air. It will be understood, however, that it is necessary only that the air spaces should be such as to secure the prompt and free flow of air 65 from the outlet side of the tube belt.

It is not necessary that the number and spacing of the tubes should be uniform from inlet to outlet side of the belt, and in some cases it may be desirable to place the tubes 70 nearer each other on the outlet side or to gradually decrease the tube spacing from the inlet to the outlet side, or otherwise provide for less free flow on the outlet side than on the inlet side of the belt. The decrease in 75 tube spacing toward the outlet side allows

for the steam condensed nearer the inlet side and the maximum condensation from each tube is thus secured with a large tube surface in the same condenser dimensions or with a reduction in condenser size.

70

In the construction shown in Fig. 1, one end of the tube belt joins the casing above the air offtake *a* and the opposite end of the belt joins a perforated or slotted plate *b* arranged at the bottom of the condenser above 75 the hot-well, this spray or rain plate *b* joining the casing on the air offtake side of the condenser, so that the air offtake *a* is enclosed by the tube belt and spray plate. The tube bank formed by the belt is separated 80 from the casing on the opposite side from the air offtake *a* so as to leave steam space 12 extending to the bottom of the casing and below the spray plate *b*, thus supplying heating exhaust steam through the condensate 85 falling in divided or spray condition from the spray plate *b*. The perforations or slots in the plate *b* must be sealed or of such character that the resistance to the air flow 90 through them will be in excess of the steam resistance to the steam flow through the tube bank, so as to avoid short-circuiting the steam through the plate to the air chamber and air offtake *a*. As shown in Fig. 8, the 95 perforations shown diagrammatically in the other figures, are sealed by being enclosed in a trap kept filled with the condensate and from which the water overflows through the perforation. Fig. 8 shows a form suitable for the horizontal plates *b*, in which the plate opening is sealed by a rim 2 covered by a cap 3. Fig. 8^a shows a form suitable for vertical or inclined portions of a plate *b*, in which the overflow is from a trough 4 enclosing the opening 1.

100

In Fig. 2 the construction is the same as in Fig. 1, except that the two ends of the tube belt D are connected to the spray plate *b* at opposite sides of the latter and steam passages 12 are provided at opposite sides 110 of the belt for the passage of steam to the space below the spray plate and the hot-well. In this construction, the air offtake *a* is shown as arranged between the central portion of the tube bank and spray plate.

115

The construction shown in Fig. 3 is substantially the same as that shown in Fig. 2, except that the lower portion of the condenser casing is bow-shaped, curving into the hot-well, and the spray-plate *b* is correspondingly curved and of greater length.

120

The construction shown in Fig. 4 employs two tube belts D arranged on opposite sides of the condenser, each enclosing its air offtake *a*, and the ends of the two tube belts are connected to the two spray plates *b*, *b'* arranged one above the other at the bottom of the condenser, so that the two tube belts D and the two spray plates *b*, *b'* enclose the air offtakes, steam spaces 12 for

125

supply of steam below the spray plates and to the hot-well being provided between each tube bank and the casing.

Fig. 5 shows a construction similar to Fig. 2, but with the tube bank D arranged in a circular condenser so as to leave space for an air chamber of considerable size above the spray plate b, and this air chamber contains an air cooler 14 covered by a plate 15 preferably of V-form, as shown, which acts to exclude the falling condensate from the air cooler, the air passing from the air chamber upward around the lower edges of the plate 13 to the air offtake a.

The construction shown in Figs. 6 and 7 are of the same general character shown in Fig. 5, but with the tube bank and air cooler modified somewhat in form, and the condenser casing of the rectangular type, the construction in Fig. 7 being similar to that shown in Fig. 4 in providing a large central steam space for admission of the steam to the folds of the tube belt arranged on opposite sides of the condenser.

It will be understood that the condensate spray plate may be used with other arrangements of tubes and is thus claimed, and that all features of the invention may be embodied in many other constructions differing in form and arrangement from those shown, and that the invention is not to be limited to the constructions illustrated, but includes all other constructions within the scope of the invention as defined by the claims.

What is claimed is:

1. In a steam condenser, a tube bank consisting of a shallow belt of tubes extending between the exhaust inlet and air outlet, and a condensate spray plate extending over the lower part of the condenser, said tube belt being arranged to provide space for the passage of exhaust steam to the lower side of the spray plate.

2. In a steam condenser, a tube bank consisting of a shallow belt of tubes extending between the exhaust inlet and air outlet and arranged in folds providing steam spaces on the inlet sides of the folds and air spaces on the exit sides of the folds, and a condensate spray plate extending from one end of the tube belt over the lower part of the condenser, said tube belt being arranged to provide for the passage of exhaust steam to the lower side of the spray plate, and means for preventing the flow of steam through the spray plate from its lower side.

3. In a steam condenser, a tube bank consisting of a shallow belt of tubes extending between the exhaust inlet and air outlet and arranged in folds providing steam spaces on the inlet sides of the folds and air spaces on the exit sides of the folds, and a con-

densate spray plate extending over the lower part of the condenser, said tube belt 65 being arranged to provide contracting steam spaces on the inlet sides of the folds and expanding air spaces on the exit sides of the folds.

4. In a steam condenser, a tube bank consisting of a shallow belt of tubes extending between the exhaust inlet and air outlet, a condensate spray plate extending from one end of the tube belt over the lower part of the condenser, said tube belt being arranged 70 to provide space for the passage of exhaust steam to the lower side of the spray plate, and an air offtake on the outlet side of the tube belt enclosed by the tube belt and spray plate.

5. In a steam condenser, a tube bank extending between the exhaust inlet and air outlet, and a condensate spray plate extending over the lower part of the condenser, said tube bank being arranged to provide 75 space for the passage of exhaust steam between the casing and tube bank to the lower side of the spray plate.

6. In a steam condenser, a tube bank extending between the exhaust inlet and air outlet and a condensate spray plate extending over the lower part of the condenser, said tube bank being arranged to provide 80 for the passage of exhaust steam to the lower side of the spray plate, and means for 85 preventing the flow of steam through the spray plate from its lower side.

7. In a steam condenser, a tube bank extending between the exhaust inlet and air outlet, a condensate spray plate extending 100 over the lower part of the condenser, said tube bank being arranged to provide space for the passage of exhaust steam between the casing and tube bank to the lower side of the spray plate, and an air offtake on the outlet 105 side of the tube bank enclosed by the tube bank and spray plate.

8. In a steam condenser, a tube bank extending between the exhaust inlet and air outlet, and a condensate spray plate extending over the lower part of the condenser, said tube bank and spray plate being arranged to provide a steam space surrounding the tube bank and spray plate.

9. In a steam condenser, a tube bank consisting of a shallow belt of tubes extending between the exhaust inlet and the air outlet, and a condensate spray plate extending across the condensate outlet in spaced relation thereto, said tube belt being arranged to provide space for passage of steam to the space between the spray plate and condensate outlet.

In testimony whereof, I have hereunto set my hand.

CHARLES E. LUCKE.
